GOOGLE FRAME AND METHOD OF
MAKING THE SAMECharles J. Haag, Carlstadt, N. J., assignor to
Columbia Protekosit Co., Incorporated, Carl-
stadt, N. J.

Application April 6, 1935, Serial No. 14,996

13 Claims.

(Cl. 88—42)

This invention relates to articles of manufacture such as goggle frames or similar devices and to methods of making the same.

One object of the invention is to provide a device of the character described having few and simple parts, and which is inexpensive, durable, reliable, neat, compact and efficient in use to a high degree.

Another object is the provision of a device of the nature set forth wherein soldering, welding, riveting, and like expensive operations shall be eliminated and improved connecting means provided for a continuous member having unbroken and even article retaining flanges.

Another object of the invention is the provision of pins or tongues on a goggle lens frame which shall be received between, and project away from each other through perforations in the flanges of a rigid nose piece so as to be conveniently bent over on the flanges at the outside of the nose piece, and which tongues shall be received in said perforations without bending or forcing the tongues thereto, but rather by suitable manipulation of the frame itself.

Another object of the invention is to construct a goggle lens frame having integral tongue means for the nose piece connection and the frame adapted to continuously uniformly engage the lens in a conventional manner.

Another object is to provide improved features as follows: Tongue forming cutouts the flange portions at which are reenforced by the lens; flat non-twisted integral tongues reenforcingly engaged with the nose piece; cutouts between and concealed by the tongues and nose piece; tongues direct connected to the main frame sections.

Further objects of the invention are to provide improved methods for realizing the foregoing objects of the improvement in the structure, the steps described being subject to modification, variation, and substitution by equivalent steps.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a view in front elevation showing a device embodying the invention.

Fig. 2 is a fragmentary top plan view of the connecting means.

Fig. 3 is an enlarged fragmentary sectional view taken on the line 3—3 of Fig. 1.

Fig. 4 is a fragmentary enlarged isometric view of parts of the device in disconnected but corresponding relationship, one of the frames being deformed preliminary to connection with the nose piece.

Fig. 5 is a fragmentary edge view of the deformed frame portion according to a slightly modified construction.

Fig. 6 is a fragmentary view in rear elevation of a modification of the invention.

Fig. 7 is a fragmentary view in rear elevation of another modification of the invention.

Fig. 8 is an enlarged fragmentary isometric view of a portion of the same in course of manufacture.

Fig. 9 is a fragmentary view in edge elevation of another modification of the invention in its first step of manufacture.

Fig. 10 is a view in rear elevation of the completed article, with parts in section.

Fig. 11 is a fragmentary top plan view of the invention showing the means for attaching a temple.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 15 denotes a device embodying the invention and which may consist of a frame including one or more frame sections such as 16 and a part such as 17 to be connected to one or both of the frame sections. A novel means is employed for connecting a frame section with the part referred to. The utility and advantage of the invention and the method for its manufacture is well exemplified in a goggle frame. Thus the frame sections 12 consist of one piece structures of sheet material, such as a relatively pliable thin metal, drawn into continuous uniform channel shape and curved to receive lens elements such as 18 that may consist of colored glass. Each frame section is split as at 19 to afford outward extending projections or flattened ears 20 adapted to

be received in a sheet metal clip 21 for pivotally attaching a temple 22 as by a pin 23 passing through ears 20 and holes in the clip flanges and a hole in the temple. The temple is received 5 between the ears 20, and the latter afford a degree of resilience to frictionally engage the temple. The clip 21 has a pair of upper and lower flanges 24 between which the ears are received, and an end closure flange 24a bent at a line 26. 10 A feature of the construction is that the flanges 24 have alined recesses 25 to receive the adjacent portions of the frame 16 to prevent rotation of the clip about the pin 23 and maintain the ears 20 taut by exerting a stretching action, if desired 15 between the pin 23 and the frame at the recesses 25. If preferred, the pin 23 may be a headed screw threaded into one of the flanges 24 to draw the flanges together to clamp the ears 20 and the temple therebetween. 20 The part 17 may constitute any suitable bridge or nose piece, which may consist of relatively stiff sheet metal and may include the nose rest 27 as an integral part thereof. Specifically, the nose piece may comprise a front panel or plate 28 25 and top and bottom parallel flanges 29, 30, from the latter of which the nose rest may extend in an upwardly and inwardly curved manner, with side recesses provided at 31 and laterally extending nose seating wings 32. The nose piece 17 30 in effect constitutes a one piece channel element, in the flanges of which are spaced holes 33 alined in the upper and lower flanges.

Cut, pressed, or struck out from the back 34 51 of each channel section 16 are one or more elongated tongues or pins 35 affording shanks that extend outward in the same general direction 35 toward the nose piece. These tongues 35 result in the formation of openings or slots 36 longitudinal of the channels 16, and the arrangement 40 is such that said openings 36 lie between the tongues 35 to be concealed between the tongues and nose piece 17. The width of a tongue 35 is substantially equal to the width of the back of 45 the channel, but the side flanges 37 of the latter are continuous and unbroken at the openings 36 and close said openings, to uniformly engage and retain a lens 18 without any difference in the conventional uniform appearance of the device. 50

As a result of the openings 36, the flanges 37 55 are deformable laterally for a purpose later described. To avoid consequent undue weakness in the frame and to provide a degree of reenforcement for the flanges 37, the openings 36 are preferably discontinuous or spaced from each other, as by an intermediate strap or portion 38 of the back 34 of the channel.

Since the tongues 35 are relatively pliable, they 60 are not only entered into corresponding holes 33 but bent over on flanges 29, 30 for a secure interlock. To facilitate such interlocking, the tongues have bent end portions 39 that extend away from each other, whereby the ends 39 can be bent over on the flanges 29, 30 on the outside 65 of the nose piece. Thus the tongues 35 constitute preformed L or hook shaped elements.

To facilitate entry of the tongues 35 between the flanges 29, 30, without manipulating the hook ends 39, the frame 16 is contracted as shown at 40, as by spreading apart the flanges 37 at the openings 36. Now the hook ends 39 can be received 70 between the flanges 29, 30, alined with the holes 33. Upon restoring the frame to initial condition, as by removing the deformations or bulges 40, by pressing the same inward to increase the 75 spacing between the tongues to that which initial-

ly obtained, thereby the hook ends engage in and project from the holes 33, and can be readily bent over as shown at 41. The lens 18 may now be inserted into the frame member 16, the temple clip and pin applied, and the goggle is complete, with the lenses re-enforcing and tensioningly stiffening the frames at the cut outs. 5

It will be understood that the strap 38 may be eliminated if the tongues 35 are closely spaced, but ought to be used if relatively widely spaced 10 to prevent the edge of the lens from projecting into the opening between the tongue, resulting in looseness of the lens and possible breakage thereof. The wide spacing is desirable to afford rigidity at the nose piece. 15

The ends 42 of the flanges 29, 30 may be close to the backs 34 of the channels to limit relative swing between the sections 16 and the nose piece.

According to Fig. 5, hooked pins 35c are soldered to the back of the channel frame and the latter deformed and restored to normal with the aid of an opening in the back especially provided for that purpose, all according to the method hereinbefore described. 20

In Fig. 6 is shown a modification of the invention which is different from that hereinabove described only in that the tongues 35a hook inward into the nose piece, and hence the step of forming and eliminating the deformations 40 need not be practised. However, it is more difficult to bend 30 the tongue ends 39a. 25

In Fig. 7 is shown a modification which is like the device 15 except that the tongues 35b are formed with end ears 43, to receive pins 44 that pass therethrough and the holes 33 of the nose 35 piece. 30

In Figs. 9 and 10 is shown a modification wherein in a plurality of tongue portions 45 are formed on a tongue means 46 struck from the back of the channel, and so as to leave a projection 47, if 40 desired, in the plane of said back to support an edge of the lens. The tongue means 46 is thus flexible and can be laterally deformed with the flanges 37 as shown at 40 in Fig. 4; or a flange 29 can be bent up and then down to cause the 45 alined pin or tongue portions 45 to engage holes 33. The portions 45 need not be bent over, since the tongue means acts as a spacer and re-enforcement therefor. The tongue means 46 also reenforces the flange 37b from which it extends 50 at any desired acute angle or at a right angle.

It will be appreciated that various changes and modifications may be made in the device as shown in the drawing, and that the same is submitted in an illustrative and not in a limiting sense, the 55 scope of the invention being defined in the following claims.

I claim:

1. In a goggle, a one piece channel frame of pliable sheet material for receiving a lens, the back 60 of said channel frame having an opening between the flanges of the channel frame, attachment elements spaced longitudinally of the channel frame and being individually connected to said back at the ends of said opening and having shanks projecting outwardly from the channel frame, said attachment elements having ends projecting in opposite directions at an angle to said shanks and along the plane of the channel frame, and said flanges being continuous and adapted to be 65 deformed toward and away from each other at said opening to vary the spacing between the attachment elements to permit said ends of the elements to be engaged in fixedly spaced holes. 70

2. In a goggle, a one piece channel frame of 75

5 pliable sheet material for receiving a lens, the back of said channel frame having an opening between the flanges of the channel frame, spaced attachment elements integrally connected to the 10 channel frame at the ends of said opening and having shanks projecting outwardly from the channel frame, said flanges being continuous and pliable and adapted to be deformed toward and away from each other at said opening to vary the 15 spacing between the attachment elements, and a lens of rigid material, said channel frame receiving and being secured along said lens to afford support for the flanges at said opening.

3. In a goggle, a one piece sheet metal channel frame, the latter having a plurality of spaced elongated tongues, each of said tongues being integral with the back of the channel and each affording an opening in said back extending longitudinally of the frame, said channel frame having 20 flanges continuous at said openings, said openings being between the tongues and being spaced to afford a lens retaining strap therebetween interconnecting said flanges, said tongues projecting outwardly from the channel frame in 25 the same general direction and having their ends bent away from each other to project in opposite directions, a nose piece having fixedly spaced flanges provided with holes to receive said ends, and said channel flanges being deformable at said 30 openings to permit the said tongues to be moved toward and away from each other to cause said ends to be received between said spaced nose piece flanges and then to enter said holes thereof and to project through said holes so as to be adapted 35 to be conveniently bent over the faces of the flanges remote from each other.

4. The method of attaching to a pliable sheet metal member an article having fixedly spaced perforated portions by means of tongues connected to the member and projecting away from each other to engage between the said portions in the 40 perforations, which includes, forming in said member a closed opening, collapsing said member at said opening to diminish the space between said tongues so that the latter can be received between the portions, and then causing said member to assume its initial shape with said tongues being simultaneously received between said portions and entered in said holes.

5. The method of attaching to a channel member of sheet material an element having fixedly spaced perforated portions by means of tongues connected to the member and projecting away from each other to engage between the portions and in the perforations thereof, including cutting an opening in the back of the channel member between the tongues and the opening being substantially the full width of the said back and elongated therealong, maintaining the continuity 55 of the channel flanges at said opening, laterally bending said flanges at said opening to diminish the distance between said tongues so that the same can be received between the said portions, then restoring said flanges to initial shape to 60 move said tongues apart to enter into said perforations.

6. The method of making a goggle lens channel frame of relatively thin pliable material and connecting the same to a nose piece having spaced 65 perforated flanges, including striking out spaced tongues from a back of the channel frame to afford an opening longitudinally thereof for weakening the flanges of the channel frame without affecting the continuity of the flanges, forming bends in said tongues, laterally deforming

5 said flanges at said opening to shorten the distance between said tongues so that the same are receivable between said nose piece flanges with the bent portions enterable in the perforations, and finally removing said deformations to increase the space between the tongues to cause the same to engage in said perforations.

7. A goggle including a nose piece frame, and a goggle frame of channel form in cross section and consisting of relatively pliable sheet metal, 10 the back of said channel frame having a pair of spaced cutouts affording tongues integrally connected to the back of the channel at those ends of the cutouts that are remote from each other, said tongues being outwardly bent and interconnecting the goggle frame and the nose piece frame substantially at opposite ends of said pair of spaced cutouts, the channel flanges being continuous at said cutouts and being integrally interconnected by a back portion of the channel 15 frame intermediate of said cutouts, and a lens of rigid material, said channel frame receiving and being tensioned around said lens so that the same prevents collapse of the channel flanges at 20 said cutouts.

8. A goggle including a pliable sheet metal goggle channel frame, the back of said frame having tongue forming cutouts with the tongues connected to said back at the remote ends of said cutouts, said cutouts being confined wholly between the flanges of the channel frame and said flanges being continuous at said cutouts, said 25 tongues being outwardly bent at an angle to said back and being substantially parallel to each other.

9. A goggle including a pliable sheet metal goggle frame of continuous channel form in cross section, said frame having tongue forming cutouts in the back thereof, said tongues being bent outwardly, the flanges of the channel frame being 40 continuous at said cutouts, a lens of rigid material peripherally embraced in said channel frame, the latter being tensioned around the lens, and the lens reenforcing said flanges at the cutouts, and a nose piece of rigid material, having spaced 45 perforations, said tongues having their ends in hooked engagement with the nose piece in said perforations, and said tongues being of flat shape in transverse cross section, so that said tongues, which are free of twist, are braced between the 50 channel frame and the nose piece.

10. A goggle including a nose piece frame and a lens holder of channel form in cross section, the back of said channel holder having a pair of spaced cut outs affording tongues integrally connected to the back of the channel at those ends of the cut outs that are remote from each other, said tongues being outwardly bent and interconnecting the lens holder with the nose piece frame at opposite ends of said pair of spaced cut outs, 55 and the channel flanges being continuous at said cut outs and being integrally interconnected by a back portion of the channel frame intermediate of said cut outs.

11. A goggle including a channeled frame element of sheet material adapted to extend along and to be secured to a lens, the back of said frame element having cut outs affording flat elongated tongues with the tongues connected to said back at the remote ends of the cut outs, said cut outs being confined substantially between the flanges of the channel frame and said flanges being continuous at said cut outs, said tongues being flatwise outwardly bent at an angle to said back, a nose piece having rigid spaced perforated flange 70 75

portions in end abutment with the frame element, said tongues having hooked ends extending through the respective perforations and bent flat over on the flange portions toward the frame element so that the nose piece reenforces the tongues.

12. A goggle including a channeled frame element of sheet material adapted to extend along and to be secured to a lens, the back of said frame element having cut outs affording flat elongated tongues with the tongues integrally connected to said back at ends of the cut outs, said cut outs being confined substantially between the flanges of the channel frame and said flanges being continuous at said cut outs, said cut outs being spaced 15 to provide an intermediate portion integrally interconnecting the flanges at the cutouts, said tongues being flatwise outwardly bent at an angle to said back, a nose piece having rigid spaced flange portions in substantial end abutment with the back of the channel element, said flange portions having aligned perforations, said tongues having their end portions bent flatwise to provide hooks, said hooks extending snugly through the respective perforations and being rearwardly bent along the flange portions so as to extend 20 toward the frame element.

13. In a goggle, a one piece sheet metal channel

frame, the latter having a plurality of spaced elongated tongues, each of said tongues being integral with the back of the channel and each affording an opening in said back extending longitudinally of the frame, said channel frame having flanges continuous at said openings, the said openings being between the tongues and being spaced to afford a lens retaining strap therebetween interconnecting said flanges, said tongues projecting outwardly from the channel frame in 10 the same general direction and having their ends bent away from each other to project in opposite directions, a nose piece having fixedly spaced flanges provided with holes to receive said ends, and said channel flanges being deformable at 15 said openings to permit the said tongues to be moved toward and away from each other to cause said ends to be received between said spaced nose piece flanges and then to enter said holes thereof and to project through said holes so as to be adapted to be conveniently bent over the faces of the flanges remote from each other, said nose piece being of rigid material and the flanges thereof having end abutment with the back of the 20 channel frame.

CHARLES J. HAAG.
